Primary Examiner — Ricky Pham

(57)

CLAIM

The ornamental design for milk steamer, as shown and described.

DESCRIPTION

1. Milk steamer

1.1 : Front

1.2 : Back

1.3 : Left

1.4 : Right

1.5 : Top

1.6 : Bottom

1.7 : Perspective

1.8 : Exploded

1.9 : A-A cross-sectional

1.10 : B-B cross-sectional

1.1 to 1.10 are drawings showing an embodiment of the milk steamer; 1.9 is a cross-sectional view taken along the A-A line shown in 1.8; 1.10 is a cross-sectional view taken along the B-B line shown in 1.8; the present product is used for

(Continued)

whipping milk quickly to form foam; The broken lines form no part of the claimed design.

1 Claim, 10 Drawing Sheets
